DESIGN FOR A CLOTHES DRIER

Hyman S. Aaronson, Meridan, Conn.

Application May 18, 1943, Serial No. 110,231

Term of patent 14 years

(Cl. D49—1)

To all whom it may concern:

Be it known that I, Hyman S. Aaronson, a citizen of the United States of America, residing in Meridan, county of New Haven, and State of Connecticut, have invented a new, original, and ornamental Design for a Clothes Drier, of which the following is a specification, reference being had to the accompanying drawing, forming part thereof.

The figure on the drawing is a front perspective view of a clothes drier, showing my new design.

The rear of the drier, not shown, is substantially plain.

I claim:

The ornamental design for a clothes drier, substantially as shown and described.

HYMAN S. AARONSON.
